FUME HOOD

Marion D. Taylor, Berkeley, Calif., assignor to
 Shell Development Company, San Francisco,
 Calif., a corporation of Delaware

Application September 19, 1947, Serial No. 774,930

7 Claims. (Cl. 98—115)

1

This invention relates to fume hoods of the cabinet type and is, more particularly, concerned with an improved hood suitable for use in laboratories where light and/or heavy fumes of noxious or disagreeable properties are generated and must be withdrawn through an exhaust duct.

Cabinet type fume hoods provided with vents for discharging light and heavy fumes from the top and bottom of the cabinet are already known. (See, for example, U. S. Patent No. 1,934,808.) Such fume hoods are installed in laboratories and industrial establishments to permit chemical and physical processes involving the generation or discharge of fumes to be carried out. The main purpose of using such hoods is to prevent the escape of such fumes into the space surrounding the hood, e. g., into the laboratory room. Heretofore hoods have been designed particularly to facilitate the withdrawal of the fumes from various parts of the space within the hood, and the purpose has been to cause the fumes to move backward, i. e., away from the front; for this purpose the intakes or at least some of the intakes to the suction duct have been located near the back of the hood. While such hoods are effective to draw off fumes from within the hood, they have not been fully effective in preventing the fumes from drifting out from the front of the hood unless the front closure is shut.

According to the present invention it was found that fumes can be more effectively prevented from escaping out from the front of the cabinet when the closure is open by drawing the fumes off at the front instead of at the sides or rear, it being the distinguishing feature of this invention that a strong suction effect is provided at the front. In the preferred embodiment of the invention the heavy fumes are caused to flow toward the front of the cabinet and then downwardly around the forward edge of the work bench, and the bench is fitted closely against the sides and rear of the cabinet to provide no other drawoff point. It is also possible to employ auxiliary drawoff apertures in the bench or in the sides or rear of the cabinet; however, it was found that, with a given capacity of the duct system to which the hood is connected, the use of such auxiliary drawoff apertures or vents dissipates the available vacuum and that better results are obtained by applying substantially all of the available suction at the front of the cabinet. While heavy fumes may to a certain extent collect at the rear of the cabinet with such an arrangement, they are not objectionable at that location, and the main object of using a

2

fume hood, viz., the escape of fumes into the space surrounding the hood, is achieved more effectively.

The instant invention has, for an object, the improvement of the heavy vapor drawoff system whereby heavy vapors or fumes are more effectively prevented from flowing out of the front of the fume hood when the front closure is open. A further object is to provide an improved fume hood of the cabinet type which is suitable for full-length use, without a counter, as well as for use with a counter, as desired, which is arranged for the drawoff of light and/or heavy fumes, as desired.

15 The improved fume hood according to this invention comprises a dam at the front of the cabinet rising a suitable distance, e. g., 2 to 5 inches or more, above the level of the work bench, and installed so as to be in position regardless of 20 whether the front closure of the cabinet above the dam is closed or is open to permit access to the equipment within the cabinet. A vent for causing a down draft is provided at or near the dam to draw off heavy fumes and prevent them 25 from accumulating on the work bench to a height sufficient to overflow the dam.

In one embodiment of the invention, the fume hood comprises a cabinet forming a working chamber and provided with suction vents at the top and at the bottom, the vents being connected with either to separate suction ducts or to a common duct; the cabinet is provided with a removable or adjustable counter, positioned between said vents and the bottom of the cabinet may, 30 optionally, form a bottom or lower work bench. The front closure is constructed to provide a dam or baffle extending above the bottom of the working chamber, regardless of whether this bottom be the adjustable counter or, when the 35 counter is removed, the lower bench at the bottom of the cabinet. A heavy vapor draw-off space or slot only between the forward or outer edge of the working counter and the dam or baffle whereby a more effective removal of the 40 heavy fumes is effected.

According to another embodiment of the invention the suction vent at the bottom of the cabinet is arranged along the dam at the front of the hood.

50 The invention will be better understood from the following detailed description, taken together with the drawings forming a part of the specification and illustrating one preferred embodiment of the invention, wherein:

Fig. 1 is a front elevation view of the improved fume hood;

Fig. 2 is a vertical sectional view taken on the line 2—2 of Fig. 1;

Figs. 3 and 4 are horizontal sectional views taken on lines 3—3 and 4, respectively, of Fig. 2;

Fig. 5 is a vertical, sectional view, similar to Fig. 2, showing a modified construction, and

Fig. 6 is a horizontal sectional view taken on line 6—6 of Fig. 5.

Referring to Figs. 1—4 of the drawings, the fume hood comprises a supporting base 1 having a lower bench 2, side walls 3, and a rear wall 4 and a roof 5, forming a working chamber. A drain trough 6 is recessed in the lower bench and may be connected to a liquid discharge line, such as a sewer, not shown. A false back wall or partition 7 extends substantially the full height of the cabinet and has its upper portion inclined forwardly. A draw-off duct 8 at the top of the cabinet, provided with an adjustable damper 9, may be connected by means of a connecting duct, not shown, to some means of suction, such as a fan. The space between the walls 4 and 7 forms a heavy vapor drawoff duct, such vapors entering this duct at the bottom through the opening or vent between the drain trough and the bottom of the wall 7. This opening may be adjusted by means of an adjustable damper 10. An adjustable damper 11 at the top of the wall 7 permits the vent between the top of the cabinet and the vent to be adjusted.

A removable shelf or counter 12, forming an upper work bench, is mounted at an intermediate level by means of support 13 secured to the wide walls. The supports 13 are disposed at different levels to permit the counter to be adjusted to different heights, the counter being shown in its upper position. When the counter is installed, it divides the cabinet into a working space above the counter and into a heavy fume collecting chamber beneath the counter. The counter 12 is in engagement with the side walls 3 and the false wall 7 but its forward edge is set back of the lower bench 2, as explained hereinafter. A fixed baffle 14 extends along the front of the cabinet 2 forming a transverse dam. The top of the baffle 14 is preferably above the level of the counter 12 when the latter is in its lower position. A similar baffle 15 extends downward from the roof. The space between the baffles 14 and 15 is closed by three panels which may be window sashes mounting shatterproof glass panes. The upper (outer) sash 16 may be removable or fixed to the cabinet; the intermediate (inner) sash 17 and the lower sash 18 are vertically slideable in sash frames on the side walls 3. The sashes 16 and 17 may be mounted in the forward-most and rear-most sash frames, respectively, as shown, to provide a slot between them through which air may enter the cabinet at a point intermediate to the top and bottom of the working chamber. The lower sash 18 is of such a height as to extend above the level of the removable counter 12 when in its lower position, thereby forming a dam or baffle to prevent heavy vapors from drifting out of the cabinet even when the intermediate (inner) sash 17 is raised. It extends upwardly only through a minor portion of the height of the working chamber, e. g., 2 to 5 inches, whereby access to the chamber is not obstructed. Sash 18 is positioned so as to leave a space or vent 19 between the front edge of the counter and the sash. The bottom of the sash 18 fits inside of the baffle 14.

The intermediate (inner) sash 17 closes the space between the upper and lower sashes except for the slot between it and the sash 16. Sashes 17 and 18 are disposed as shown in Fig. 2 so that both may be raised to positions behind the upper (outer) sash 16, thereby affording access to the cabinet. A conduit 20 is mounted on the side walls 3 and discharges into the trough 6. It is provided with inlets 20a, providing a table-height drain.

When the fume hood is in use a suction is applied to the duct 8 and fumes are drawn into it from the top and bottom of the hood in accordance with the setting of the dampers 10 and 11. The space at the top of the cabinet behind the upper (outer) sash 16 and baffle 15 forms a light fume collecting space from which the fumes are drawn off.

When the fume hood is used for operations at table-height, the counter 12 is installed as shown and the lower sash 18 is in its lower position. The space beneath the counter 12 now forms a fume collecting chamber for heavy vapors, which enter downwardly through the space or vent 19 and are drawn off past the damper 10 and through the heavy vapor drawoff duct behind the wall 7. This flow will occur regardless of the position of the intermediate (inner) sash 17. When, however, this sash is in its raised position, the arrangement described above is particularly advantageous because it was found that heavy fumes are best prevented from leaving the hood by applying a strong suction near the front of the counter, and by providing a dam, such as is formed by the upwardly extending portion of the sash 18. By providing the vent 19 substantially only at the front a more effective suction can be attained at this point with a given vacuum at the duct 8 than when providing vents also at the sides and rear of the counter.

When the hood is used as a full height hood the counter 12 is lowered to its lower position, or removed entirely. In this use the lower sash 18 may be in its lower or raised position, and with the counter in its lower position heavy fumes enter the heavy vapor drawoff duct as before. When the sash 18 is raised the baffle 14 prevents such fumes from drifting out toward the front of the cabinet. When the counter 12 is removed from the cabinet heavy fumes are not drawn forward, but enter the lower vent at the rear directly.

The dampers 10 and 11 may be adjusted in accordance with the nature of the fumes to be drawn off. Thus, when only light fumes are to be drawn off, the damper 11 is open and the damper 10 may be partially or entirely closed; conversely, when only heavy fumes are to be drawn off, the damper 10 is open and the damper 11 may be partially or entirely closed. In other situations the dampers may be adjusted to provide simultaneous draw-off of light and heavy fumes. It was found that the damper 10 may in certain cases be omitted because when the damper 11 is fully open a negligible amount of vapor is drawn in from the bottom with a moderate vacuum on the vent 8.

Referring to Figs. 5 and 6, like reference characters indicate parts previously described for Figs. 1 to 4. In this embodiment the lower vent is arranged in the form of a sheet iron duct 21 secured to the inner face of the lower baffle 14 having a narrow longitudinal aperture 22 facing downwardly to prevent the entrance of liquid. The duct 21 is connected by connect-

ing ducts 23 at the sides of the cabinet to the duct 8. If desired, dampers 24 may be provided.

The embodiment according to Fig. 5 may be used with the counter 12 in the manner previously described. When the counter 12 is removed entirely for using the fume hood as a full height cabinet, this form provides suction at the front of the cabinet at the dam or baffle 14, for preventing the overflow of heavy fumes from the front of the cabinet when the sashes 17 and/or 18 are in their raised positions.

I claim as my invention:

1. A fume hood comprising a cabinet having side walls, a rear wall and a roof, a lower bench at the bottom of said cabinet near the floor level, a drain trough for liquid at the bottom of the cabinet, a removable working bench at an intermediate level of the cabinet near table height forming a working chamber thereabove and a heavy fume collecting chamber therebeneath, a drain having its intake within said working chamber and discharging into said drain trough, duct means for withdrawing fumes from the bottom of said collecting chamber and from said working chamber, an adjustable damper above said drain trough for regulating the passage of heavy fumes from said collecting chamber into said vent, and a vent between said working chamber and said collecting chamber.

2. A fume hood comprising a cabinet having side walls, a roof and double rear walls forming a duct therebetween, a lower bench at the bottom of said cabinet, a vertically adjustable imperforate working bench at an intermediate level of the cabinet, fitting closely against the sides and rear of the cabinet and dividing the cabinet into a working chamber thereabove and a heavy fume collecting chamber therebeneath, communicating vents between the bottom of said collecting chamber and said duct and between the top of the working chamber and said duct, damper means for regulating the passage of fumes through said vents, a transverse baffle at the bottom of the cabinet extending across the front of the collecting chamber and forming a first dam extending upwardly from the lower bench for a portion only of the height of said chamber, a second transverse baffle at the top of the cabinet extending across the upper portion of the working chamber, and a front closure for the cabinet comprising a pair of vertically slidable panels, one for the working chamber and the other for the collecting chamber, the latter panel being spaced from the removable bench to provide a vent for the downward flow of heavy fumes from the working chamber into the fume collecting chamber and being of such height as to extend, when in its lower position, to above the level of the removable working bench through a minor portion of the height of the working chamber to provide a second dam.

3. A fume hood comprising a cabinet having side walls, a rear wall, and a roof and containing a working bench at an intermediate level, said bench defining above itself a working chamber within the cabinet, the front of the working chamber being adapted to be at least partially open to afford access thereto; a drawoff duct in communication with said working chamber above the bench for drawing off light fumes from said working chamber; and means for drawing heavy fumes generated within said working chamber forwardly along said bench to the front of the cabinet and thence downwardly without escape through said open front comprising

ing a baffle extending across the front of the cabinet to form a fume dam rising upwardly through only a minor portion of the height of the working chamber but through a substantial height sufficient to prevent the escape of heavy fumes at the front of the cabinet, a vent opening along the front of the bench and in rear of the baffle for the downward passage of fumes, and an elongated, confined duct extending transversely across the cabinet beneath the front of the bench and immediately in rear of the dam, said duct being apertured along the length thereof to receive heavy fumes from said vent opening and to apply a suction to the working chamber through said vent.

4. A fume hood comprising a cabinet having side walls, a rear wall and a roof; a lower bench at the bottom of said cabinet near the floor; a removable working bench at an intermediate level of the cabinet near table height defining a working chamber above itself and a fume collecting chamber beneath itself and the lower bench, the front of the working chamber being adapted to be at least partially open to afford access thereto; a light fume drawoff duct in communication with said working chamber above the working bench for drawing off light fumes from said working chamber; a heavy fume drawoff duct communicating with said collecting chamber beneath the working bench for drawing off heavy fumes therefrom; a baffle extending across the front of the lower bench and forming a first fume dam extending upwardly from the lower bench for a portion only of the height of the collecting chamber but through a substantial height to retain heavy fumes therein against escape from the front; and a first movable closure for said collecting chamber extending across the front thereof and disposed to close the front of said chamber above said first baffle and extending upwardly in front of and above the level of the working bench through a minor portion of the height of the working chamber but through substantial height sufficient to prevent the escape of heavy fumes from the working chamber at the said open front thereof to form a second heavy fume dam; a second movable closure extending across the front of the working chamber and rising upwardly from the top of the second fume dam for closing the front of the working chamber; and a vent opening along the front of the working bench in rear of the second dam, said collecting chamber being isolated from said working chamber by said working bench except for said vent opening whereby heavy fumes generated within said working chamber will be drawn forwardly along said bench to the front of the cabinet and thence downwardly through said vent opening into the collecting chamber for evacuation through the heavy fume drawoff duct.

5. A fume hood comprising a cabinet having side walls, a rear wall and a roof; a lower bench at the bottom of said cabinet near the floor; a removable working bench at an intermediate level of the cabinet near table height defining a working chamber above itself and a fume collecting chamber beneath itself and the lower bench, the front of the working chamber being adapted to be at least partially open to afford access thereto; a light fume drawoff duct in communication with said working chamber above the working bench for drawing off light fumes from said working chamber; a heavy fume drawoff duct communicating with said collecting

chamber beneath the working bench for drawing off heavy fumes therefrom; a baffle extending across the front of the lower bench and forming a first fume dam extending upwardly from the lower bench for a portion only of the height of the collecting chamber but through a substantial height to retain heavy fumes therein against escape from the front; and a vertically slidable closure for said collecting chamber which when in its lowered position rises from said first baffle to a height well above the level of said working bench at the intermediate level to form a second heavy fume dam preventing the escape of heavy fumes from the working chamber at the said open front thereof, but through only a minor portion of the height of the working chamber to provide access thereto, said closure extending fully across the front of the cabinet; and a vent opening along the front of the working bench in rear of the second dam, said collecting chamber being isolated from said working chamber by said working bench except for said vent opening whereby heavy fumes generated within said working chamber will be drawn forwardly along said bench to the front of the cabinet and thence downwardly through said vent opening into the collecting chamber for evacuation through the heavy fume drawoff duct.

6. The fume hood according to claim 5 wherein

the heavy fume drawoff duct comprises an elongated, confined duct within the collecting chamber extending transversely with respect to the cabinet in rear of the baffle at the front of the cabinet and near the lower bench, said duct being apertured along the length thereof to receive heavy fumes from said vent opening and from said lower bench.

7. The fume hood according to claim 5 wherein the said slidable closure is spaced forwardly from the front edge of the working bench to provide a slit-like space between itself and the bench, the said space constituting the said vent opening.
